KEROSENE HEATING UNIT

John P. Theisen, Jacksonville, Ill., assignor to New York
Shipbuilding Corporation, New York, N. Y., a corpo-
ration of New York

Application February 25, 1955, Serial No. 34,728

Term of patent 14 years

(Cl. D81—10)

Fig. 1

Fig. 2

Figure 1 is a perspective view of a kerosene heating unit, embodying my new design; and

Figure 2 is a top plan view thereof.

The portions of the unit not shown are the same as those shown.

I claim:

The ornamental design for a kerosene heating unit, substantially as shown and described.
